UNITED STATES PATENT OFFICE.

ROBERT F. DAVIS, OF MORLEY, MISSOURI

GRIST-MILL.

1,201,269.

Specification of Letters Patent. Patented Oct. 17, 1916.

Application filed January 3, 1916. Serial No. 69,975.

To all whom it may concern:

Be it known that I, ROBERT F. DAVIS, a citizen of the United States, residing at Morley, in the county of Scott and State of Missouri, have invented a new and useful Grist-Mill, of which the following is a specification.

The device forming the subject matter of this application is a grist mill adapted to 10 be employed for grinding grain and like material, the structure being intended primarily although not exclusively for domestic use.

The invention aims to improve the construction of the burs, to provide novel means for adjusting the positions of the burs, to provide novel means for rotating the burs, and, generally, to improve and to enhance the utility of devices of that type to which 20 the present invention appertains.

With the above and other objects in view which will appear as the description proceeds, the invention resides in the combination and arrangement of parts and in the 25 details of construction hereinafter described and claimed, it being understood that changes in the precise embodiment of the invention herein disclosed can be made within the scope of what is claimed, without departing from the spirit of the invention.

In the accompanying drawing:—Figure 1 shows in longitudinal section, a grist mill embodying the present invention, parts appearing in elevation; Fig. 2 is a side elevation of the grist mill forming the subject matter of this application; Fig. 3 is a horizontal section of the grist mill, parts appearing in elevation; Fig. 4 is a diagram showing one of the burs.

40 In carrying out the present invention there is provided a supporting structure 1 on which is mounted a bed plate 2, the latter being held to the supporting structure by means of securing elements 3.

45 Formed integrally with the bed plate 2 is a circular body 4 having in its opposite sides, frusto-conical bores 5, the smaller ends of which lie adjacent the vertical axis of the body 4. At the ends of the bores 5,

50 recesses 6 are fashioned, and from the recesses 6 lead discharge chutes 7. Above the bores 5, the body 1 is provided with a conical bottom 8 at the lowermost point of which is disposed an opening 9 communicating with the bores 5. At its upper end, the body 4 is provided with a flange 10 retaining

a hopper 11. The body 3 is surrounded by a pair of approximately semi-circular casing members 12 provided with ribs 28 received in recesses 29 formed in the body 4, 60 to hold the casing members in place. The casing members 12 are supplied with fillets 14 from which project ears 15 connected by bolts 16, the casing members 12 being thus held about the body 4 to constitute 65 closures for the recesses 6.

Threaded into the casing members 12 and projecting into the recesses 6 are bearings 17 provided with hand wheels 18, whereby the bearings may be moved endwise for a 70 purpose to be pointed out hereinafter. The bearings 17 may be held in adjusted positions by means of lock nuts 19 threaded onto the bearings and adapted to bear against the casing members 12. Journaled for rotation in the bearings 17 is a main shaft 20, provided at one end with a pinion 21 carrying a flange 22. The pinion 21 meshes into an internal gear 23 formed on a drive wheel 24 journaled for rotation on a stub 75 shaft 25 projecting from a lug 26 constituting a part of the body 4, the wheel 24 being held on the stub shaft 25 by means of a nut 27 or the like. The flange 22 coacts with the inner edge of the wheel 24 and constitutes 80 a means whereby the main shaft 20 is prevented from moving to the right, referring to Fig. 1. The drive wheel 24 may be rotated through the medium of a handle 30 or, if desired, a belt (not shown) may be 85 trained about the periphery of the wheel 24, when it is desired to drive the wheel from a gasoline engine or other prime mover. Secured to one end of the main shaft 20 is a gear wheel 31 meshing into a 90 pinion 32 fixed to a shaft 33 journaled for rotation in the supporting structure 1. The pinion 32 is provided with an outstanding flange 34, adapted to coöperate with the outer face of the gear wheel 31, thereby to 95 limit the movement of the main shaft 20 toward the left, referring to Fig. 1. Secured to one end of the shaft 33 is a fly wheel 35. The shaft 33 may be employed for driving a bolting mechanism, but since 100 such a structure cannot be claimed in the present application, along with a grinding means, no bolting mechanism has been 105 shown or described.

Surrounding a portion of the main shaft 110 20 and located in the frusto-conical bores 5 of the body 4 are frusto-conical burs 36 pro-

vided internally with recesses 37. The burs 36 are held to the main shaft 20 for rotation therewith, through the instrumentality of keys 38, the construction being such that, 5 through a mechanism to be described hereinafter, the burs 36 may be adjusted toward and away from each other, the burs sliding longitudinally of the keys 38. The burs 36 are provided with teeth 39, the teeth being 10 spaced more widely from each other adjacent the smaller ends of the burs than adjacent the wider ends of the burs, as indicated diagrammatically in Fig. 4. The frusto-conical bores 5 in the body 4 are 15 equipped with suitably shaped teeth, indicated at 40 and adapted to coöperate with the teeth 39 on the burs. Applied to the ends of the burs 36 are end plates 41 held in place by securing elements 42. Housed 20 within the recesses 37 of the burs 36 are compression springs 43, the inner ends of which bear against the keys 38, the outer ends of which bear against the end plates 41. The end plates 41 are engaged by the threaded 25 bearings 17.

In practical operation, the material to be ground is dumped into the hopper 11 and passes by way of the opening 9 into the frusto-conical bores 5, the material therein 30 being macerated or ground by the action of the teeth 40 in the bores 5 and the teeth 39 on the burs 36. The ground material flows into the recesses 6 and leaves the recesses 6 by way of the chutes 7.

35 Rotation is imparted to the main shaft 20 and to the burs 36 by means of the pinion 21 and the internal gear 23 of the drive wheel 24, it being observed that when the drive wheel 24 is rotated in a clockwise direction, the main shaft 20 and the burs 36 will be rotated in a clockwise direction also.

The fineness of the grist may be regulated by adjusting the burs 36 toward and away from each other. The springs 43 tend to 45 move the burs 36 outwardly, away from each other, thereby to increase the coarseness of the grist. In order to move the burs 36 toward each other, thereby to render the grist finer, the bearings 17 are rotated, the 50 same advancing and bearing upon the end plates 41, the burs 36 thus being thrust toward each other. The bearings 17 may be held in adjusted positions by manipulating the lock nuts 19, so that the same bear upon

the casing members 12 as hereinbefore described. 55

Having thus described the invention, what is claimed is:

1. In a grist mill, a body provided with opposed frusto-conical bores, the smaller 60 ends of which are disposed adjacent the vertical axis of the body; opposed screws threaded into the body; nuts on the screws and coacting with the body; a shaft journaled for rotation in the screws; opposed 65 frusto-conical burs secured to the shaft to rotate therewith, and located in the bores, the burs having recesses in their outer ends; compression springs in the recesses and coacting at their inner ends with the shaft; 70 and removable closures for the recesses and located on the outer ends of the burs, the closures being engaged by the screws, and constituting abutments for the outer ends 75 of the springs.

2. A grist mill comprising a body; a shaft journaled for rotation in the body; burs 80 slidable longitudinally of the shaft and operating within the contour of the body; springs engaged at their outer ends with the burs; means on the shaft for receiving the inner ends of the springs; means for limiting the outward movement of the burs; a drive wheel journaled for rotation on the body and provided with an internal gear; 85 a pinion carried by the shaft and meshing with the internal gear, the pinion having a flange coacting with the inner edge of the drive wheel, thereby to prevent the shaft from moving in one direction due to unequal efforts of the springs; a second shaft journaled for rotation in the body; a gear 90 wheel carried by the first specified shaft; a pinion carried by the second shaft and meshing into the last specified gear wheel, 95 the said pinion being provided with a flange coacting with the outer face of the last specified wheel, to prevent the first mentioned shaft from moving in an opposite direction due to unequal efforts of the springs. 100

In testimony that I claim the foregoing as my own, I have hereto affixed my signature in the presence of two witnesses.

ROBERT F. DAVIS.
